UNITED STATES PATENT OFFICE

WALTER A. SAATMAN, OF ROSLYN, PENNSYLVANIA

ADJUSTABLE APRON FEED FOR GLUE MACHINES

Application filed July 24, 1926, Serial No. 124,650. Renewed March 12, 1930.

My invention relates to machines for gluing and delivering sheets of paper for application usually to boxes in box-making machines and then called wraps, but capable of broader application, and has particular reference to the motion of the delivery mechanism used to deliver glued wraps from the gluing machine to the box-wrapping machine.

10 A purpose of my invention is to make adjustable the distance of movement of the conveyor apron corresponding to the gluing of each wrap.

15 A further purpose is to control the length of time between the application of the glue to the wrap, and the application of the glued wrap to a box, by controlling the distance of feed of the conveyor per stroke of the wrapping machine.

20 A further purpose is to vary the number of glued wraps between the glue machine and box-wrapping machine, usually having more glued wraps upon the conveyor when the wraps are small than when they are large.

25 Further purposes will appear in the specification and in the claims.

Figure 1 is a transverse section through driving and feeding mechanism of a glue machine, and illustrates one form of my invention. The section is upon line 1—1 of Figure 2, looking in the direction of the arrows.

Figure 2 is a section taken upon the line 2—2 of Figure 1 looking in the direction of the arrows.

30 Figure 3 is a fragmentary section of Figure 2 taken upon the line 3—3 looking in the direction of the arrows.

Figure 4 is a section of Figure 2 on the line 4—4 looking in the direction of the arrows.

40 Figure 5 is a section of Figure 4 taken upon the line 5—5 and looking in the direction of the arrows.

Figure 6 is a section upon the line 6—6 of Figure 4 looking in the direction of the arrows.

45 Figure 7 is a side elevation of the conveyor structure shown by me.

50 Figure 8 is a section of Figure 7 taken upon the line 8—8 looking in the direction of the arrows.

Figure 9 is a section taken on line 9—9 of Figure 7 looking in the direction of the arrows.

Like numerals refer to like parts in all figures.

Describing in illustration and not in limitation and referring to the drawings:

A suitable motor, F² is coupled at F³ to a worm F⁴ mounted in bearings F⁵ within gear casing F⁶ upon the left side of the gluing machine as viewed from the front.

The shaft C¹⁰⁸ is extended through the gear casing and is reduced in diameter at F⁷ and also at F⁸, see Figure 2. Upon the reduced portion F⁸ of the shaft C¹⁰⁸ is mounted a sleeve F⁹ free to rotate on the shaft and supporting a worm gear F¹⁰ meshing with the worm and continuously driven by it during the operation of the motor. The gear and sleeve as a unit have bearing upon the outside of the shaft when the shaft C¹⁰⁸ is not in operation and travel with it at the same speed when the shaft C¹⁰⁸ is driven.

The worm gear F¹⁰ is extended to the right in Figure 2 to form an integral gear F¹¹ which also rotates continuously with the motor.

70 The worm gear and gear F¹¹, considered as a unit, are hollow and give place within them for a movable clutch member F¹² having inset wooden clutch bearing faces F¹³ terminating at an angle, and for a follower disc F¹⁴. The movable clutch member fits within a co-operating clutch surface F¹⁵ and is supported for longitudinal clutch engagement movement along the reduced portion F⁷ of shaft C¹⁰⁸ by a hub sleeve F¹⁶ which has longitudinal movement along but no rotation on the shaft.

The follower disc F¹⁴ fits within a recess F¹⁷ upon the inside of the gear F¹¹. On one face it is recessed at F¹⁸ at intervals to provide seats for spiral springs F¹⁹ by which it presses the movable clutch member towards clutch engaging position, which therefore is the normal position of this movable clutch member except as disengaged by other means.

80 A stud F²⁰ in the follower disc passes through an opening F²¹ in the clutch member and drives the clutch member. It is free to slide in the opening to accommo- 100

date differences in spacing between them. On the opposite side the disc F^{14} is grooved to form the internal cam C^{64} .

The disc is hubbed at F^{22} to give additional support upon the shaft and is keyed to the shaft at F^{23} . The same key is used to fasten to the shaft a gear F^{24} which rotates with the shaft.

Upon the shaft C^{108} to the right of the gear F^{24} in Figure 2, Sheet 2, is mounted a hub F^{25} upon which is carried the gripper cam C^{81} .

In order to provide for continuous rotation of the gluing mechanism the teeth of gear F^{11} engage the teeth of the gear F^{26} splined at F^{27} to a shaft F^{28} , rotatable and also movable longitudinally in bearings F^{29} , F^{30} in the gear case and frame respectively. The shaft F^{28} carries an enlarged end F^{31} upon which is mounted a clutch member F^{32} adapted to engage the clutch member E^{63} .

The end of the shaft F^{28} is grooved at F^{33} for engagement by a fork or projection F^{34} upon a hand lever arm F^{35} pivoted at F^{36} in a projection $F^{36'}$ from the gear casing. The shaft may thus be slid back out of clutch engagement with the clutch member E^{63} and is held in its several positions by a latch F^{37} fitting into openings F^{38} in the shaft and spring pressed into engagement with the shaft by a spring F^{39} secured to the gear hub F^{40} by screws F^{41} .

When the gluing mechanism is intended to be disconnected, whether preparatory to swinging it out of its position or not, the hand lever F^{35} is thrown to the left in Figure 2 to release the clutch.

As will be seen the feed cylinder and the gluing mechanism have continuous operation during the time the clutch member F^{12} is in engagement with the clutch surface F^{14} . The feed cylinder is stopped at the end of each rotation and is held until released by tripping mechanism provided. On the other hand the apron is intended to be actuated during a part only of the time of rotation of the feed cylinder travel, and though it must start at the same position of feed cylinder travel, we have provided adjustment of the extent of feed to correspond with differences in the lengths of the wraps as hereinafter described.

The drive for the apron conveyor

With clutch engagement the gear F^{24} is driven continuously. As will be seen from Figure 1, Sheet 1, the gear is one of a pair of intermittent stop-motion gears whose mating gear F^{42} is carried by a stud F^{43} (Figure 5) secured in the frame of the machine by nut F^{44} bearing against washer F^{45} . This stud carries also a gear F^{46} which is rigid with and preferably integral with intermittent gear F^{42} . Of the two outer gears F^{24}

and F^{42} , F^{24} is the driving gear. It is also the larger gear and, through each carries the same number of teeth, the teeth occupy a smaller part of the circumference of gear F^{24} than of gear F^{42} to permit the lost motion between the two gears to take place in the second outer gear F^{42} rather than within the first which must travel with the shaft. The outer gear F^{24} , therefore, in conjunction with teeth F^{47} has a relatively large free surface F^{48} of diameter approximately the pitch diameter of the teeth, which surface engages with a small arcuate portion F^{49} between the ends of teeth F^{50} upon gear F^{42} , during which engagement gear F^{42} is held in stationary position. These gears are frequently called intermittent gears and are comparable with the intermittent gears of commerce.

The directions of rotation are shown by the arrows in Figure 1. As in the case of other features of our invention the form shown is a selected form only among many which will serve the purpose, which brings the mating gears around to the same position for each turn and permits lost motion between them so that the driving gear can rotate continuously so long as the shaft rotates while the driven gear F^{42} is provided with a rest or dwell.

For the purpose of smoothing the beginning of the driving and driven engagement of the intermittent gears, we provide a quickening contact between the pin F^{51} carried by the rear of the disc F^{14} and the walls F^{52} of slot in projection F^{53} from the otherwise free face of gear F^{46} . The projection is held against rotation upon the gear by screws F^{54} . Just before engagement of the teeth of the driving intermittent gear with the teeth of the driven intermittent gear, the pin F^{51} enters the slot of the revoluble pin F^{52} and gradually increases the speed of this pin and hence of the driven intermittent gear until the teeth of the two intermittent gears have met and mesh at the same speed. The lost motion between the walls of the slot and the pin permits the driven intermittent gear to speed up with respect to the pin in the driving gear from this point.

Each rotation of the driven intermittent gear F^{42} , causes a rotation of the gear F^{46} (Figure 2 and Figure 6) rigid with it and causes considerably more rotation of a gear F^{55} meshing with gear F^{46} , since gear F^{46} is much larger than gear F^{42} . Gear F^{55} is rigid with a face clutch F^{56} and between them is a groove or neck F^{57} . Both the gear and face clutch rotate freely upon a shaft F^{58} which is keyed at F^{59} through a collar F^{60} to a sleeve F^{61} terminating in a face clutch F^{62} co-acting with the face clutch.

It will be noted that the gear F^{55} rotates during a part only of the rotation of the feed cylinder, dwelling for the remainder of the rotation of this cylinder, and that the face

clutch F^{62} is driven for a part only of the time of rotation of the gear F^{55} .

The face clutch F^{56} and its integral gear F^{55} are shifted by means of an arm F^{63} mounted upon and guided by the pin F^{64} sliding in opening F^{65} and spring pressed toward clutch engaging position by a spiral spring F^{66} . The spring presses against a shoulder F^{67} upon the head F^{68} of the pin F^{64} and holds the clutch faces of F^{56} and F^{62} normally in engagement. The head and spring lie within a pocket F^{69} in the frame of the machine. The gear F^{55} is given additional width to ensure continued complete engagement with the teeth of gear F^{46} .

The head F^{68} upon pin F^{64} projects beyond the frame for operating engagement by one end F^{70} of a rocking arm F^{71} pivoted upon a pin F^{72} rigid with the frame for the purpose of disconnecting the two clutch faces F^{56} and F^{62} . The pin F^{72} is held in position by the set screw F^{73} .

The lower end F^{74} of this rocking lever F^{71} engages a pin F^{75} (Figure 5) supported in sleeve F^{76} which is carried by a sliding rod F^{77} operated by handle F^{78} . The rod is notched at F^{79} to receive a latch bolt F^{80} pressed to position by spring F^{81} . The rod slides in a guide formed between the boss F^{82} in the frame and a plate F^{83} secured to the frame. As will be noted the spring pressed pin F^{64} holds the pin F^{75} normally in position shown in Figure 5 with its end F^{84} projecting beyond the plate at differing distances from the axis of the stud F^{42} according to the setting of the sliding rod.

The pin end F^{84} thus projects in the path of a stepped face cam F^{85} so as to be pressed longitudinally (away from the observer as it appears in Figure 5) by any one of the stepped cam faces F^{86} — F^{89} , Figure 4, according to the radial distance from the axis of the stud which is also the axis of the cam.

The cam in the construction seen in Figure 5 is mounted upon a sleeve F^{90} integral with gear F^{46} . The gear F^{42} is also mounted upon this sleeve and for convenience in assembling the sleeve and gear F^{46} are held to the pin by a separate head F^{91} , screw 92 and pin F^{93} .

Whatever the position of the pin F^{75} corresponding to different settings of the rod F^{77} , the pin is engaged by one of the face cam surfaces F^{86} — F^{89} with the same effect of disconnecting the clutch faces F^{56} and F^{62} and, hence, stopping the conveyor apron movement. This disengagement is maintained until the cam has turned to the position shown in Figure 4 where the end F^{84} of the pin F^{75} is released from the cam at the cam edge F^{94} when the re-engagement of the clutch faces seen in Figure 6 starts the apron conveyor action.

Because the apron conveyor should start at the same time in each movement, what-

ever its distance of movement, the edge F^{94} extends nearly radially to allow the pin to be released from the face cam at the same angular position of the face cam within the adjustment radially of the rod and pin F^{75} . This uniform starting position for the apron conveyor is timed to correspond with the beginning of delivery of a wrap from the glue-applying roll to the apron and the speed of the apron is arranged to correspond with the speed of movement of the wrap so that the apron will receive the length of the wrap continuously without tendency to fold or slide the wrap upon the apron.

With the uniform starting position of the apron as indicated, the difference in radial distance of the pin F^{75} from the axis of the cam and stud pin F^{42} is effective for the purpose of adjusting the length of movement of the apron conveyor before disconnection of its driving clutch F^{56} . As will be seen from Figure 4, the different angular distance about the cam in a counter-clockwise direction between the edge F^{94} and the several face cam surfaces F^{86} — F^{89} represent different proportions of the time of rotation of the cam during which the conveyor feed apron is operated.

Main clutch tripping mechanism

The disconnection of the clutch faces F^{13} from the co-operating clutch surface F^{15} , the main clutch mechanism of the machine, may be accomplished in two ways, the one tripping to stop the feeding mechanism after each complete rotation of the feed cylinder and the other to stop the feeding mechanism independently of movement of the tripping lever.

The hub F^{16} is grooved at F^{95} to provide a seat for a radially projecting rib F^{96} upon a pin F^{97} passing through the sleeve F^{9} and hence rotating with the worm gear F^{10} . This pin F^{97} is normally spring pressed toward the left in Figure 2 by reason of the spring pressure against the movable clutch member F^{12} , but, if moved to the right, carries the movable clutch member longitudinally of the shaft C^{108} and against the pressure of the springs F^{19} .

Within the path of revolution of the rod F^{97} , is located a cam F^{98} rigid with a bearing pin F^{99} which turns within the gear casing at F^{100} . The construction is best seen in Figures 2 and 3.

The cam carries a cam face F^{101} which is swung by turning of the pin F^{99} into or out of the path of movement of rod F^{97} but is normally pressed into the path of movement of this rod F^{97} by a nose F^{102} spring pressed at F^{103} .

Upon the outer end of pin F^{99} , an operating lever F^{104} is located by which the cam face F^{101} is swung out of tripping position, the spring pressed nose returning it to trip-

ping position so as to throw the clutch. This releases the rod F^{97} from the cam, permitting main clutch engagement and resulting in corresponding complete rotation of the movable clutch member F^{12} and hence of shaft C^{108} until the rod F^{97} comes around again to clutch disengaging position where its engagement with the cam face F^{101} releases the clutch. Each tripping movement of lever F^{104} therefore permits one complete rotation of the feed cylinder with corresponding movement of the connected parts relating to the wrap feeding mechanism and including the feed apron. The extent of movement of the feeding mechanism is the same, but the extent of movement of the apron varies according to the setting of the pin F^{75} .

When it is desired to shut off the machine so that its feeding mechanism will not respond to movement of the tripping lever, this is accomplished by turning a screw F^{105} , as by hand wheel F^{106} , so as to cause its end to bear upon rod F^{107} at the center of shaft C^{108} . This rod engages a transverse bar F^{108} which terminates at opposite ends in sleeve F^{16} and passes through an elongated opening F^{109} in the shaft. Pressure upon the bar by reason of the screw releases the main clutch and holds it released against the pressure of springs F^{19} without regard to the position of the tripping lever.

If the tripping lever F^{104} be held in turned position, the feeding mechanism will operate continuously. The gluing rolls are independently controlled by lever F^{25} and in addition for their movement depend upon maintaining the gluing mechanism in closed position to engage clutch member E^{62} and E^{63} . During each rotation of the feed cylinder, the intermittent gear F^{24} causes movement during part of the time to intermittent gear F^{42} with corresponding rotation of the step cam F^{85} and of the gears F^{46} and F^{55} . The step cam controls the movable clutch member F^{56} to permit engagement of this clutch for a part of the time of rotation of gear F^{55} .

Suitable oil cups are provided for the mechanism such as are shown at F^{110} and drainage for the gear case takes place by removal of plug F^{111} .

The apron conveyor—group G

The conveyor mechanism for the wraps is best shown in Figures 7 and 8.

The shaft F^{88} is supported at its end opposite to the clutch F^{62} in a bearing G^1 and adjacent this bearing carries a roller G^2 forming one end of a conveyor support of which the opposite roller is located at G^3 . Adjacent the bearing and preferably at both sides of the conveyor belt are mounted pipes G^4 fitting in sockets G^5 rigid with the frame.

The pipes are pinned within the sockets by horizontal pins G^6 and may be adjusted slightly about the pins to maintain them in

any desired approach to horizontal position by set screws G^7 passing through the sockets and bearing upon the upper rear ends of the pipe.

Within the pipes G^4 telescope pipes $G^{4'}$ 70 which carry the bearings G^8 for the shaft G^9 upon which the roller G^3 is mounted. What we have called pipes $G^{4'}$ may in fact be solid or hollow providing they give abutment to one end each of springs G^{10} which press 75 against pins G^{11} within the pipes G^4 so as to stretch taut an apron conveyor belt G^{12} upon which the wraps are intended to be delivered. The bearings are suitably oiled, for which purpose oil cups are shown.

Beneath the conveyor belt G^{12} , we mount a table G^{15} to afford a rest and support for the apron belt where the wraps are intended to be placed about the boxes or other articles covered by hand. This table may be placed 85 at any desired point along the belt, having sliding support upon the pipes G^4 , forked terminals G^{13} at the end of table-supporting members G^{14} fitting over the pipes G^4 and adapting the table to be slid to any desired 90 position.

At an intermediate point along the length of one of the pipes, I mount a bracket G^{16} by means of a sleeve clamp G^{17} held in place by set screw G^{18} so as to permit longitudinal 95 movement and sufficient swinging to secure accurate alignment in planes perpendicular to the apron. The bracket is provided with a bar G^{19} upon which fits a bearing G^{20} upon a bracket G^{21} of a reservoir G^{22} . The bearing is adjustable along the bar G^{19} and is held in adjusted position as to the setting along the bar and as to pressure by set screw.

At the lower end of the reservoir are provided standards G^{24} within which a shaft G^{25} 105 is fixed by set screws G^{26} . The shaft supports a roll G^{27} whose edge is V-shaped as at G^{28} . This roll and its mechanism is adjusted by movement of the reservoir and its bracket along the rod so as to place the V-shaped wheel at approximately the center of the wrap as it is being delivered and is for the purpose of creasing the wrap along the center of its length so as to prevent it from curling in a longitudinal direction. Within the reservoir is placed a moistened sponge or similar device G^{29} to wipe the edge of the wheel so as to keep it from sticking to the paper and from depositing any glue received upon the paper.

The apron is placed in position to receive the wraps as they are discharged, the glue side up, from the glue-applying roll. As previously indicated the apron feed during the time of discharge corresponds with the speed of movement of the wrap and the length of feed is adjustable so that it may be made to correspond approximately with the length of the wrap.

Since the wraps must remain upon the

apron until they have been fed to the box wrapping or other wrap using position for use, the length of feed of the apron for each wrap must be made great enough to prevent undue drying of the glue upon the wraps where the machine is not worked at full speed or where for any other reason the wraps are not used promptly.

This length of feed of the apron for each 10 gluing machine feed operation is controlled as indicated by the face cam.

It will now be apparent that I have devised a new and useful adjustable apron feed for glue machines which embodies the features 15 of advantage enumerated as desirable in the statement of the invention and the above description, and that while I have, in the present instance, shown and described a preferred embodiment thereof which will give 20 in practice satisfactory and reliable results, it is to be understood that this embodiment is susceptible of modification in various particulars without departing from the spirit or scope of the invention or sacrificing any of 25 its advantages.

Having thus described my invention what I claim as new and desire to secure by Letters Patent is:—

1. In gearing, a motor, a worm driven 30 thereby, a worm gear driven by the worm and having a clutch face therein, a clutch spring-pressed to separate therewith, a shaft within the clutch and turning with it, a feed member on said shaft, an intermittent gear 35 carried by said shaft, a stud, a pair of gears on the stud, coupled together and one an intermittent gear engaging the first intermittent gear, a slidable gear engaging the second of the pair of gears, a clutch member 40 rigid with the slidable gear, a co-operating clutch member, and clutch operating mechanism and connections for sliding the slidable gear, timed to engage the gears in a predetermined position of the feed member.

2. In gearing, a motor, a worm driven 45 thereby, a worm gear driven by the worm and having a clutch face therein, a clutch spring-pressed to co-operate therewith, a shaft within the clutch and turning with it, a feed member driven by said shaft, a clutch controlled conveyor, intermittent gearing between the shaft and the driving clutch member of the conveyor clutch and automatic means for throwing the clutch.

3. In gearing, a motor, a worm driven 55 thereby, a worm gear driven by the worm and having a clutch face therein, a clutch spring-pressed to co-operate therewith, a shaft within the clutch and turning with it, a feed 60 member driven by said shaft, a clutch controlled mechanism, intermittent gearing between the shaft and the driving clutch member of said mechanism clutch, automatic means for throwing the clutch and an adjustment between the shaft and clutch for vary-

ing the length of time the clutch is engaged.

4. In a driving mechanism, a trip-operated clutch, a feed cylinder connected therewith, driving mechanism for one of the clutch members, gearing connected with that clutch member, mechanism driven by the gearing, a clutch between the gearing driven by the driven member of the first clutch, a conveyor operated thereby, a clutch between the said gearing and the conveyor, a plurality of clutch-release automatic operating mechanism for said clutch and selective means for applying any of said release mechanism to said clutch.

5. In a machine of the character described, 30 driving mechanism, a belt conveyor, a clutch member connected with the conveyor, a movable co-operating clutch member, a lever controlling the position of the co-operating clutch member, a pin operating the lever, and 35 a cam operating the pin to determine by cam actuation the proportionate time of operating of the machine during which the conveyor feeds.

6. In a machine of the character described, 30 driving mechanism, a belt conveyor, a clutch member connected with the conveyor, a movable co-operating clutch member, a lever controlling the position of the co-operating clutch member, a pin operating the lever, a 95 plurality of cams adapted for engagement one at a time with the pin in different positions thereof, determining different extents of feed of the conveyor for each article fed from the machine and means for selecting the 100 cam which engages with the pin.

7. In a machine of the character described, a driving mechanism, feeding mechanism driven thereby, a belt conveyor, a clutch member connected with the conveyor, a movable 105 co-operating clutch member, a lever controlling the position of the co-operating clutch member, a pin operating the lever, a plurality of cams adapted to actuate the pin in differing pin position and for different lengths of time, one end of each of the cams registering with the same position of the feeding mechanism and means for moving the pin to engage selectively any one of the cams.
